UNITED STATES PATENT OFFICE

OTTO C. SCHROEDER, OF CHICAGO, ILLINOIS, ASSIGNOR TO HENRY L. SCHROEDER, OF CHICAGO, ILLINOIS

PHONOGRAPH CABINET AND HORN

Application filed May 15, 1924. Serial No. 713,426.

This invention relates to phonograph cabinets and the sound amplifying horn for phonographs, and has for its object the provision of such devices which provide economy 5 of space and improved tone effects, and which are of improved construction and operation. The invention is exemplified in the combination and arrangement of parts shown in the accompanying drawings and described in the following specification, and it is more particularly pointed out in the appended claims.

In the drawings—

Fig. 1 is a front elevation of a phonograph cabinet embodying one form of the present 15 invention;

Fig. 2 is a vertical section on line 2—2 of Fig. 1;

Fig. 3 is a vertical section on line 3—3 of Fig. 2; and

Fig. 4 is a horizontal section on line 4—4 of Fig. 3.

Fig. 5 is a detail plan view of the cabinet showing the tone arm of the phonograph connected through the medium of an adapter 25 with the radio receiver.

In phonograph cabinets as previously constructed it has been usual to divide the cabinet space into two compartments through one of which the sound amplifying horn passes 30 to an opening at the front of the cabinet. The other compartment is commonly employed for storing records. In cabinets of the console type the two compartments are arranged side by side, while in upright cabinets 35 the two compartments are arranged one above the other.

The present invention contemplates the location of the tone amplifying horn within the compartment in which the records are 40 stored and in the embodiment shown the horn is placed in the rear of the record space. The horn is preferably given an improved form, as will be described, to improve the tone effect and to better fit within the space provided in the rear of the record space. This leaves the 45 remaining compartment free for other uses. This additional space is especially desirable for combined phonograph and radio apparatus since the receiving apparatus may be located in the additional space provided by the

present arrangement and the amplifying horn if desired may be used as a loud speaking connection for the radio apparatus.

In the drawings, the numeral 10 designates generally a cabinet of the console type having 55 a compartment 11 provided with shelves 12 on which record albums may be placed. The compartment 13 is left free for the location of radio apparatus or such other use as may be desired. The usual form of motor 14 having a crank 15 is mounted in the space above 60 the shelves 12 and drives the turntable 15' for the phonograph records.

A hollow pedestal 16 is mounted on the top 65 wall 17 which covers the compartments 11 and 13 and the usual tone arm 18 is pivoted to swing about the vertical axis of the pedestal 16 in the usual manner. The tone arm 18 carries the usual reproducer 19. The top wall 17 has an opening 20 therethrough which 70 registers with the interior of the pedestal 16 and a downwardly extending horn 21 registers with the lower face of the opening 20 and extends downwardly in the rear of the shelves 12. The horn 21 is flared so that it 75 gradually increases in cross-sectional area from top to bottom and is preferably made rectangular in cross-section to more economically fit the space in the rear of the shelves 12 and to produce desirable sound amplification.

Surrounding the lower end of the horn 80 21 is a casing 22 which is also preferably rectangular in cross-section and elongated to 85 substantially fill the space in the rear of the shelves 12. The casing 22 is provided with a deflector plate 23 located beneath the lower end of the horn 21 and provided with a central rib 24 and laterally extending curved faces 25 and 26 to divide the sound waves and direct them in two courses, laterally and 90 upwardly. The deflector plate 23 is continued upwardly to provide partition walls 27 and 28 and above these walls are additional deflector plates 29 and 30 which have curved faces deflecting the sound waves 95 downwardly through passages 31 and 32 which open through the bottom of the cabinet.

It should be noted that the cross-sectional area of the tone passage gradually increases throughout the entire length of the passage and that the double passage at the point 5 where the sound leaves the end of the horn 21 provides a combined cross-sectional area which continues to provide progressively increasing expansion of the tone passage. In this way great amplification of the sound is 10 produced and the quality of the tones is preserved.

It will be seen that the present invention not only provides an improved tone passage, but affords greater economy in the arrangement 15 of the cabinet than has heretofore been secured, thus making it possible to accommodate two sets of instruments in a cabinet of a size practically the same that has heretofore been employed for a single instrument. 20

In the embodiment shown in the drawings, a radio receiving apparatus is indicated at 35 in the chamber 13. The receiver for this apparatus may be connected to the tone arm 25 18 in the place of the reproducer 19 so that the amplifying horn 21 serves as an amplifying medium either for the radio receiving apparatus or for the phonographic reproduction apparatus. To adapt the amplifying horn 21 to the radio receiver the reproducer 19 on the tone arm 18 is removed and replaced by a so-called "adapter" 33 which is wired to the radio receiver by cord 34. Any conventional type of adapter may be used for this 35 purpose.

It will be understood that various changes in details may be made by those skilled in the art without departing from the spirit and scope of the invention and I therefore 10 do not wish to confine my invention to any specific form, except as defined in the appended claims.

I claim:—

1. A phonograph cabinet comprising a 15 pair of chambers arranged side by side, sound receiving instrumentalities located in one of said chambers, phonographic reproduction mechanism positioned above the other of said chambers, and an amplifying horn extending downwardly in the rear of said last-mentioned chamber and adapted to be selectively connected to either the sound receiving instrumentalities or the phonograph reproducing mechanism.

2. A phonograph comprising a pair of 20 chambers arranged side by side, radio receiving apparatus positioned in one of said chambers, storage shelves arranged in the other of said chambers, phonographic reproduction apparatus arranged above said last-mentioned chamber, and an amplifying horn adapted to be selectively connected to said radio receiving apparatus and said phonographic reproduction apparatus, said amplifying horn being located in the rear of said

shelves and opening downwardly through the bottom of said cabinet.

3. A sound reproducing instrument comprising a cabinet having a storage compartment at one side thereof, an amplifying horn arranged in the rear of said compartment, a reproducing instrument positioned above said storage compartment, and a reproducing instrument of a different character arranged at one side of said storage compartment said amplifying horn adapted to be selectively connected to one or the other of said instruments. 70

4. A sound reproducing instrument comprising a cabinet having a storage compartment at one side of the front thereof, radio reproducing mechanism disposed at the other side of said cabinet, a phonographic reproducing instrument disposed above said storage compartment, and an amplifying horn arranged in the rear of said storage compartment and adapted to be selectively connected to either the radio reproducing mechanism or the phonographic reproducing instrument. 80

5. A phonograph cabinet comprising a 85 pair of chambers arranged side by side, radio receiving apparatus positioned in one of said chambers, storage shelves arranged in the other of said chambers, phonographic reproduction apparatus arranged above said last- 90 named chamber, an amplifying horn adapted to be selectively connected to said radio receiving apparatus and said phonographic reproduction apparatus, said amplifying horn comprising a rectangular casing opening 95 downwardly through the bottom of said cabinet, a plurality of divided sound deflectors mounted in the top of said casing, a sound horn projecting into the casing between said deflectors and terminating below the horizontal center of the casing, a deflector plate centrally disposed in the bottom of the casing 100 with respect to the horn, upwardly presented end walls on said deflector plate terminating in a vertical plane intersecting the center of the sound deflectors, and a central rib in the bottom of the deflector plate axially disposed relatively of the horn but terminating below the lower end thereof. 105

6. A phonograph cabinet comprising a 110 plurality of compartments, one of said compartments being adapted to receive a radio receiving apparatus, a second compartment abutting said first compartment for use as a storage space above which is mounted a 115 phonograph reproducing apparatus, a third compartment forming a horn having a plurality of chambers forming outlets from said horn, a common sound inlet member symmetrically arranged with respect thereto, a deflecting plate in front of said inlet arranged to deflect the sound equally to said plurality of chambers, and means connected to said inlet member adapted to be selectively connected to the radio receiving apparatus and 120 125 130

phonograph reproducing apparatus, said horn being arranged so that adjacent sides thereof are in juxtaposition with sides of said first and second compartments respectively.

5 In testimony whereof I have signed my name to this specification on this 12th day of May, A. D. 1924.

OTTO C. SCHROEDER.
